UNITED STATES PATENT OFFICE.

CLARENCE NOEL CAHUSAC, OF NEW YORK, N. Y., ASSIGNOR TO WESTERN ELECTRIC COMPANY, OF NEW YORK, N. Y., A CORPORATION OF ILLINOIS.

TESTING APPARATUS.

1,125,462

Specification of Letters Patent. Patented Jan. 19, 1915.

Application filed December 12, 1913. Serial No. 806,245.

To all whom it may concern:

Be it known that I, CLARENCE NOEL CAHUSAC, a subject of the King of England, residing at 224 West Twenty-second street, 5 in the city, county, and State of New York, have invented a certain new and useful Improvement in Testing Apparatus, of which the following is a full, clear, concise, and exact description.

10 This invention relates to fault locating sets for repairmen, and more particularly to an apparatus box for such sets.

The object of this invention is to provide a portable container and mounting means 15 for the various apparatus comprising the set, which is compact and in which all of the various pieces of apparatus desirable for making necessary tests of a cable or transmission line may be conveniently mounted 20 in a manner to be readily accessible for making connections, replacements and repairs and will be rendered harmless to the user and otherwise well protected against accidents.

25 In accordance with this invention, there is provided a receptacle divided into a plurality of compartments within which are located various of the devices necessary for making all tests required of a repairman.

30 One of the features of this invention consists in the provision of a mounting means for the apparatus, whereby parts of the apparatus, such as high tension inductive devices which might prove dangerous to 35 the user and circuit interrupters which might be of delicate adjustment, are well protected while in use or being transported.

Other features of the invention are the means for facilitating wiring, repairs and 40 replacements, and consists in mounting all of the apparatus which is connected with permanent wiring upon a single support which is removable from the container and has a hinged portion attached thereto which 45 carries a portion of the apparatus.

In the drawings—Figure 1 is a perspective view of a test set embodying the features of this invention; Fig. 2 is a view of the apparatus and a support therefor; Fig. 50 3 is a view in side elevation of the parts of Fig. 2; and Fig. 4 is a diagram of the apparatus and connection of a set embodying this invention.

As shown in the drawings, 5 designates a container of convenient form having a

hinged cover 6 and a shoulder strap 7 by means of which it may be transported.

In order to facilitate the various tests to be made upon a cable, there are provided various pieces of apparatus wired together 60 and having certain terminals of the wiring connected with binding posts and switches in order that any of the various combinations of the apparatus for the different tests may be readily obtained. 65

As a supporting means for this apparatus there is provided a T-shaped member having a vertical portion or leg 10 and horizontal portions or arms 11 and 25.

Mounted upon the leg 10 are a plurality 70 of condensers 15, 15, a high tension electromagnetic vibrator 16 and a circuit interrupter 17 which is preferably a magnetically operated device.

Mounted upon the upper face of the horizontal portion or arm 11, are a three-way switch 18, a plurality of binding posts 19, 20 and 21, a vibrating member 22 and adjusting screws 23 and 24 of the high tension electromagnetic vibrator 16. 75 80

Mounted upon the arm or horizontal portion 25 is an electromagnetic buzzer 26 and a plurality of binding posts 27, 28, 29, 30, 31 and 32. The horizontal portion or arm 25 is preferably hinged to the edge of the 85 horizontal member 11 for convenience in removing the apparatus and making connections.

All of the pieces of apparatus hereinbefore enumerated, mounted upon the supporting members 10, 11 and 25, are connected together through permanent wiring in the form of cables 35 and 36, a portion 37 of cable 35 being run through an opening in said leg 10 and connected with the parts 90 carried upon the hinged portion 25. This portion 37 of the cable 35 extends along the under portion of the member 25 and being flexible will not interfere with the swinging movement of said member 25. 95 100

The margins of the vertical supporting member 10 extend slightly beyond the edges of the members 11 and 25 and are adapted to slide in grooves 38, 38 in the opposite sides of the container 5 near one end thereof. When in this position in the container, the member 11 is flush with the top of the container 5 and covers the space between the grooves 38, 38 and the adjacent end of the container. The hinged member 25 when in 110

its horizontal position with the supporting means in the container 5 is also flush with the upper portion of the said container and forms a cover for batteries 45, 45 which 5 may be carried in the container. A partition 46 beyond the batteries 45, 45 provides a third compartment in the container in which may be carried telephone instruments and other devices such as cable exploring 10 coils which may be required in making tests. Terminals 47, 47 connected with conductors included in the cable 35 are adapted for connection with the batteries 45, 45.

As shown in Fig. 4, the high tension vibrator 16 is provided with an energizing or 15 primary winding 40 and two secondary windings 41 and 42, the terminals of which are brought out at the binding posts 19, 20 and 21, connections to the binding posts 19 and 20 being for a low voltage, while connection to the binding posts 19 and 21 will be for a high voltage. The primary or 20 energizing winding 40 of the vibrator 16 is in circuit with a source of energy 45 and the 25 three-way switch 18. With the three-way switch in its first position circuit will be closed through the high tension vibrator 16 only. With the three-way switch in its second or intermediate position, a circuit 30 is completed through both the high tension vibrator 16 and the electromagnetic interrupter 17, whereby impulses from the vibrator 16 are sent out intermittently. When the three-way switch is in its third 35 position, the high tension vibrator is cut out and the buzzer 26 is connected in circuit with the battery. The terminals 27, 28, 29, 30, 31 and 32 are used for making outside 40 connections with the buzzer 26, with the battery, with battery and a condenser, or for obtaining various other combinations of the apparatus as may be desired.

By providing a removable support upon 45 which the various pieces of apparatus are mounted, all of these pieces are readily accessible for connections, replacements and repairs and at the same time are well protected from injuries. Moreover, with such 50 an arrangement, all of the parts necessary may be connected with permanent wiring which is confined to the removable support, thereby producing a complete unit with all of the parts conveniently located and readily accessible.

55 What I claim is:

1. In a portable testing set, a container, 60 an apparatus support removably mounted in said container, said support comprising a vertical and horizontal member, and testing apparatus mounted upon said members.

2. In a portable testing set, a container,

an apparatus support removably mounted in said container, said support comprising a vertical portion fitting within said container and a horizontal portion fitting flush 65 with a portion of the top of said container, and apparatus mounted upon said vertical and horizontal portions.

3. In a portable testing set, a container, 70 an apparatus support removably mounted in said container, said support comprising a vertical member fitting within said container, a rigid horizontal member fitting into a portion of said container, a hinged portion fitting into a portion of said container, and apparatus mounted upon said vertical portion, said horizontal portion and said hinged portion.

4. In a portable testing set, a container 75 having grooves in its side walls, a removable apparatus support having a vertical member adapted to fit into said grooves, a horizontal member and a hinged member extending over a portion of said container and forming a closure therefor, and apparatus 80 mounted upon said supporting members.

5. In a portable testing set, a container, a removable apparatus support comprising a 85 vertical member, a horizontal member and a hinged member, apparatus mounted upon 90 said supporting members, and connecting means for said apparatus carried by said support.

6. In a portable testing set, a container, a 95 removable apparatus support in said container comprising a vertical member, a horizontal member and a hinged member, apparatus mounted upon said supporting members, and a flexible cable carrying conductors connecting the various pieces of apparatus 100 carried by the supporting members.

7. In a portable testing set, a container, a T-shaped member comprising a vertical and 105 horizontal members removably supported in said container, said vertical member forming with one end wall of said container a compartment, apparatus mounted upon said vertical member within the compartment formed thereby, and upon the horizontal members a fixed partition dividing the remainder of said container into two compartments, and batteries mounted in one of said 110 two compartments beneath one of the horizontal members of said T-shaped member.

In witness whereof, I hereunto subscribe 115 my name this 10th day of December, A. D. 1913.

CLARENCE NOEL CAHUSAC.
